UNITED STATES PATENT OFFICE.

STANHOPE BOAL, WILLIAM SHERMAN ROSS, AND JOHN DILWORTH, OF PIQUA, OHIO,
ASSIGNORS TO THE FAVORITE STOVE & RANGE COMPANY, OF PIQUA, OHIO, A COR-
PORATION OF OHIO.

STOVE.

Application filed January 21, 1924. Serial No. 687,415.

Our invention relates to stoves and in particular to a control for stoves.

It is the object of our invention to provide a unitary control for the burners and 5 damper of a stove, so that they may be regulated simultaneously through a single agency. It is our object to regulate one or a plurality of burners.

It is a further object of our invention to 10 provide means for indicating the position of the burner control and damper control, so that the operator can set such controls at the exact point desired.

It is the object of our invention to prevent 15 the damper being closed while the burners are operating.

It is a further object to provide such a 20 single unitary control for damper and burners, which may be operated from a point closely adjacent the user without the necessity of reaching over the stove to control the damper. It is a further object to 25 provide such apparatus in connection with an insulated oven, which will retain the heat therein for an appreciable period after the 30 burners and damper are simultaneously closed by the unitary control.

Referring to the drawings:

Figure 1 is a plan view of a stove embodying 35 our invention with the stove pipe in section and the oven partially cut away to show one of the burners and to show the insulating construction of the walls of the oven.

Figure 2 is a section on the line 2—2 of Figure 1, looking in the direction of the arrow showing in end elevation the unitary burner control.

Figure 3 is a detailed plan view with the 40 indicator plate removed, showing the unitary control and the Bowden wire control to the damper.

Figure 4 is a perspective showing the 45 Bowden wire control connected to the damper and to the unitary control.

Referring to the drawings in detail:

1 is the top of an oven, 2 is a side wall and 50 3 indicates the rear wall which is also formed into a splash plate 4.

The oven consists of an outer wall 5 and an inner wall 6, in which is placed some insulating material 7. The door 8 is also so insulated. This gives the oven substantially

a fireless cooker construction when closed. Beneath the oven may be burners of any desired character, the details of which form no part of this invention. These burners are designated 9. Each burner is connected with a valve 10, having a burner handle 11. The valves are connected to the gas supply 55 pipe 12. The special handles 11 of the burners are linked together by a control link 13, which is pivoted to them as at 14. To this link 13 is pivoted a master handle 15 which operates the control link and the respective 60 handles pivoted thereto, which control one or more burners. In the form of our invention shown the handle of one of the burners is integrally connected to the master control handle. 65

Mounted on this control link is an upwardly projecting pin 16 having a sharp edge 17. This pin travels in a slot 18 of an indicator plate 19 projecting from the front wall of the combustion chamber over the 70 valve mechanism. The operator can judge of the position of the master control handle of the damper and of the burner controls by the position of the indicating pin with respect to the indications formed on the face 75 of the indicator plate adjacent to the slot 18. The plate 19 not only serves to provide indicating means and to protect the valve mechanism, but also serves to guard the operator against flarebacks in the burners. 80

An ear 20 is formed on one side of the master handle for attachment thereto of a wire 21, which is a part of a Bowden wire control connected to the damper. This wire travels in a guide casing 22 which is attached to the stove by clips 23. 85

The remote end of this wire 21 is connected to a damper crank 24. This crank is provided with a shaft 25 projecting into the stove pipe 26 and carrying the damper 27. 90

Thus, when the master handle is moved to the right so that the pin 16 is adjacent the word "Off", the burner handles 11 are turned to close off the gas and the damper is closed by the wire 21. When the handle 100 is moved to the left, the gas is turned on and the damper is simultaneously opened until the pin 16 stands at the indication half-on, or full-on. The sharp edge of the pin 17 enables the operator to set the apparatus at 105 the exact point desired.

- The indicator plate is detachable so that the controls can be gotten at quickly. It prevents, however, any ordinary tampering with the control, so that it is impossible to close the damper with the gas on which frequently results in the flame being extinguished, due to a lack of oxygen and the consequent accumulation of gas in dangerous quantities in the oven.
- 10 By our arrangement it is also possible to adjust the damper to the exact amount necessary to furnish a requisite draft for the particular size of flame desired. This is adjusted at the factory, so that the operator cannot use her own judgment as to the damper and its relation to the size of the flame. The parts are adjusted to give maximum results at the factory.

In cooking with our invention, very little heat is necessary due to the insulated character of the oven, which prevents heat radiation. The regulation of the damper prevents unnecessary draft which would also tend to cool the oven.

25 In practice, the gas is turned on sufficiently long for any roasting or baking to begin after the article has been placed in the oven. The gas is then turned off and the damper simultaneously closed. The roasting or baking process will continue thereafter for about one and one-half hours, because the imprisoned heat in the oven continues the cooking after the gas is out.

We desire to comprehend within our invention such modifications as may be necessary to adapt it to varying conditions. 35

Having thus fully described our invention, what we claim as new and desire to secure by Letters Patent, is:

In a stove construction, the combination 40 with a combustion chamber having an exhaust flue leading therefrom, of a rotatable damper mounted in said flue, a guard plate projecting from the front wall of the combustion chamber, a plurality of burners 45 mounted in the combustion chamber and extending through the front wall thereof beneath the guard plate, a fuel-supply pipe communicating with the burners, valves beneath the guard plate controlling the communications between the supply-pipe and the burners with each valve having an angularly displaceable actuating arm and one of the arms extending beyond the guard plate to form an operating handle, a link connecting the valve arms and provided with a pin movable in a slot in the guard plate to indicate the movement of the valves, and means connecting the operating handle with the damper to turn the latter with the actuation of the valves. 50 55 60

In testimony whereof, we affix our signatures.

STANHOPE BOAL.
WILLIAM SHERMAN ROSS.
JOHN DILWORTH.
